ATTORNEY

UNITED STATES PATENT OFFICE.

EDWARD SPIEGEL, OF BROOKLYN, NEW YORK.

SHIRT-COLLAR.

1,270,067.

Specification of Letters Patent. Patented June 13, 1918.

Application filed April 1, 1918. Serial No. 225,865.

To all whom it may concern:

Be it known that I, EDWARD SPIEGEL, a citizen of the United States, residing at Brooklyn, in the city of New York, State 5 of New York, have invented new and useful Improvements in Shirt-Collars, of which the following is a specification, reference being had to the annexed drawing.

This invention relates to the construction 10 of turn down shirt collars which are starched or stiffened when worn, and the object of my improvement is to provide a turn down collar which will not cut or abrade that portion of the shirt on which the lower edge of 15 the turn down part of the collar rests.

In the drawings:

Figure 1 is a side view of my new collar as it appears when turned down; Fig. 2 is the same when opened out flat and Fig. 3 20 is a cross section on the line $x-x$ of Fig. 1.

When turn down collars are buttoned or otherwise secured to the neck band of a shirt and in use by the wearer, the lower edge of the turn down portion thereof rests on 25 the shirt and usually presses particularly on the bosom of the shirt. This is particularly so at the front of the collar. The collar is made in two main parts. A is the portion to be attached to the band of the shirt and 30 B is the part turned over as seen in Fig. 1.

The usual button holes b , b , are provided in the band portion, which preferably is composed of two layers c , c , of cloth. In 35 the turn down portion B I interpose a somewhat stiff and thick layer of material d , which abuts against a cord C, inclosed and

confined at the outer edge of the turn down portion.

The reinforcing inner lining d , extends from the cord to the point where the turn 40 down portion B meets the band part A.

Preferably I employ one line of stitching s , to confine the cord in position at the edge of the turn down portion B. This stitching is made to pass through the inner stiffening 45 piece d , close to the cord C, so as to confine the cord in position along the edge of the collar.

If desired the cord may be still further held in position by a line of stitching which 50 passes through one side of the cord C. The stiff lining d , should approach in thickness the diameter of the cord C, although it may not in all cases be so thick.

It will be seen that by my new construction, a sharp cutting surface at the lower edge of the turn down portion of the collar is obviated and the cutting or wearing of 55 the shirt front or bosom at this point is avoided.

Having described my improvement what I claim as new and desire to secure by Letters Patent is:

A turn down shirt collar comprising a band portion and a turn down part of cloth 65 secured thereto, said turn down portion having two layers of material inclosing an inner stiffening lining terminating in a cord located on the exterior edge thereof and confined by the fold of the cloth over the same 70 substantially as shown and described.

EDWARD SPIEGEL.
